US00D615494S

(12) **United States Design Patent**
Yang

(10) **Patent No.:** **US D615,494 S**
(45) **Date of Patent:** **** May 11, 2010**

(54) **BATTERY CONNECTOR CONTACT**

(75) Inventor: **Chih-Lin Yang**, Taipei (TW)

(73) Assignee: **Cheng Uei Precision Industry Co., Ltd.**, Taipei (TW)

(**) Term: **14 Years**

(21) Appl. No.: **29/350,415**

(22) Filed: **Nov. 17, 2009**

(51) **LOC (9) Cl.** **13-03**

(52) **U.S. Cl.** **D13/120; D13/154**

(58) **Field of Classification Search** **D13/103–106, D13/118–121, 133, 154, 146–147, 180, 184, D13/199; 439/83, 108, 166, 500, 577, 630, 439/660, 680, 700, 773.1, 862, 884–887, 439/890–891, 893; 429/96–100, 163, 186; 362/382, 457, 545**

See application file for complete search history.

(57) **CLAIM**

The ornamental design for battery connector contact, as shown and described.

DESCRIPTION

FIG. 1 is a perspective view of battery connector contact showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the battery connector contact showing my new design.
